UNDULATING CUT-PILE FABRIC SPLITTING
MACHINE

Jacob W. Spicks, Mystic, Conn.

Application October 20, 1938, Serial No. 235,997

1 Claim. (Cl. 26—13)

This invention relates to woven fabrics, more particularly to types such as pluses, velvets and the like, woven to produce two uniformly spaced webs, connected by fine transverse fibers, severed 5 intermediate the webs to form two independent pieces each having a furry appearance, known as cut pile fabrics.

Ordinarily, the cutting is so performed that the pile is of uniform length, that is, the ends of 10 the cut strands are level and parallel with the web in which they are interwoven throughout the entire width and length of the fabric.

An object of the present invention is to provide 15 a cut pile fabric having an undulating, wave-like face, novel with respect to the level surface of ordinary pile fabrics.

A further feature is in the provision of means 20 for cutting a woven double pile fabric intermediate its webs, so that the pile in one portion varies in length from that in another portion, whereby 25 a series of regular undulations are produced throughout the length of the piece.

These objects are attained by the novel and 30 practical mechanism hereinafter described and 25 illustrated in the accompanying drawing, constituting a material component of this disclosure, and in which—

Figure 1 is a plan view of a mechanism, made 35 in accordance with the invention, for shearing the woven double web of fabric.

Figure 2 is a sectional view taken on line 2—2 of Figure 1.

Figure 3 is a transverse sectional view of one 35 of the roller cams between which the fabric passes.

Referring in detail to the drawing, the numeral 15 designates in general the pile fabric as woven, consisting of two webs 16 and 17, between which are the interwoven pile threads 18.

40 A stand, composed of side frames 25—26, which may be part of or attached to the delivery end of a loom, is provided with bearings for a plurality of transverse shafts, on one of which 27, is secured a spur gear 28, meshed with an intermediate gear 30 on an idler shaft 31.

45 An upper feed gear 32, on shaft 33, meshes with gear 30 and also the upper gear 34 of a pair of gears, one of which, 34 is rotatable on shaft 35 and its mating gear 36 on shaft 37, the gear 36

meshing with the lower feed gear 38 on shaft 39, directly below gear 32.

A tractive roll 40 is fixed on shaft 27 to extend between the housings 25—26, and over which one of the split webs is trained, as 16. 5

Fixed on the upper driven shaft 33 is a long face cam 42, a mating cam 43, being secured on the shaft 39, and as the shafts are driven in unison, the cams operate in timed relation.

Each cam, 42—43 is shaped to produce slightly 10 raised surfaces 45 arranged longitudinally at ninety degrees apart, while therebetween are diametrically reduced spaces 46, the cams being so adjusted on their respective shafts that the raised portions of one are directly opposite the lowered 15 portions of the other, so that the fabric in passing between them is alternately raised and lowered, from a level plane, a distance corresponding to the regular undulations of the cams.

Fixed between the frame elements 25—26 is 20 a stand 48 preferably having an undercut plate surface 49, to which may be fitted a slide 50 provided with a clamp 51 by which is secured a keen bladed cutting knife 52, disposed longitudinally 25 of the cams centrally of the oncoming fabric 15.

It will now be seen that the fabric as woven, passes between the cams 42—43, by which it is moved up and down, relative to its normal plane, and therefore the pile is cut to produce an undulating surface, as at 19—20, as the web 16 is 30 drawn over the tension roll 40.

Although the foregoing is descriptive of the best known embodiment of this simple device, it is not to be held as restrictive, as many modifications may be made within the scope and tenor 35 of the appended claim.

Having thus described the invention and set forth the manner of its construction and application what is claimed as new and sought to secure by Letters Patent, is:

40 In a machine for splitting a double web pile fabric, a fixed knife, means to feed the fabric against said knife, a gear train, and a pair of rotating cams having undulated faces, one above and the other below the fabric web, closely adjacent the edge of said knife, whereby the pile threads between the webs are severed to present undulating surfaces when cut.

JACOB W. SPICKS.
